CLAIM

The ornamental design for a turkey hunter's hat, as shown and described.

DESCRIPTION

FIG. 1 is a top, front and side perspective view of a turkey hunter's hat showing my new design;

FIG. 2 is a front elevational view;

FIG. 3 is a side elevational view, the opposite side being a mirror image thereof;

FIG. 4 is a rear elevational view;

FIG. 5 is a top plan view; and,

FIG. 6 is a bottom plan view.

The indicia shown in broken lines on the cap in FIGS. 1 and 2 is for illustrative purposes only and forms no part of the claimed design. The rest of the broken lines on the cap represent conventional stitching. The surface pattern on the hat is understood to repeat throughout the indicated area.
